UNITED STATES PATENT OFFICE.

PHEE EDWARD PETERSEN, OF SEATTLE, WASHINGTON.

DERRICK.

Application filed November 13, 1920. Serial No. 423,977.

To all whom it may concern:

Be it known that I, PHEE EDWARD PETERSEN, a citizen of the United States, residing at Seattle, in the county of King and State 5 of Washington, have invented certain new and useful Improvements in a Derrick, of which the following is a specification.

This invention relates to movable derricks mounted upon wheeled supports, or trucks, 10 and has for one of its objects to simplify and improve the construction and increase the efficiency and utility of devices of this character.

Another object of the invention is to provide a device of this character having means whereby the foot or base portion of the hoisting boom may be engaged with the ground over which the truck or body is moved.

20 With these and other objects in view, the invention consists in certain novel features of construction as hereinafter shown and described and then specifically pointed out in the claims, and in the drawings illustrative of the preferred embodiment of the invention.

Figure 1 is a side elevation,

Fig. 2 is a front elevation,

30 Fig. 3 is an enlarged detail of the swivel mast coupling, and,

Fig. 4 is an enlarged sectional detail of the foot member of the mast.

The improved apparatus is mounted on a wheeled vehicle of suitable construction, 35 preferably of the motor driven class, and includes a platform 10 supported on traction wheels 11. The platform 10 is provided with a rearwardly opening recess 12, and mounted on the platform, at its rear, are standards 40 comprising side members or beams 13, connected at their upper ends to a socket device 14. The beam members 13 are outturned at their lower ends to form attaching feet 15, by which the beams are connected to the 45 platform by bolts or like devices.

The beams are thus located at opposite sides of the recess 12 and are further supported by suitable braces 16 from the platform.

50 Mounted for rotation in the socket 14 is a stud or pin 17, the latter having a perforated ear 18, and pivoted at 19 to the ear 18, is a clip device or strap 20, and slidable through the clip is a boom or mast element 21.

55 By this arrangement the boom or mast 21 is free to swing both laterally and vertically

and also free to slide longitudinally relative to the strap or clip device 20, so that it can be disposed in a substantially vertical or backwardly leaning position with the lower 60 part extending through the recess 12 of the platform as shown in full lines in Fig. 1 when in use.

The boom or mast 21 is generally of wood but may be of piping, if preferred, and at 65 its lower end is provided with a ferrule or cap 22 to receive a relatively heavy screw 23. The screw is rotatively coupled at 24 to a support 25, and rotatively coupled at 26 to the support is a ground bearing base element 70 27, the latter preferably provided with ground engaging claws 28.

By this means the base member will engage the ground flatly no matter what inclination may be imparted to the mast or 75 boom, and by rotating the screw 23 by a lever applied to its turning head, the boom may be anchored to the ground, and its steadiness and stability thus insured.

If found necessary additional brace rods 80 may be employed.

At its upper end the boom or mast is provided with a strap or clip 29 to receive the upper block or sheave of a hoisting appliance represented as a whole at 30.

Suitable pull cables 31 and tackle elements 32 are also applied to the boom to actuate the same in disposing it in operative or inoperative position.

The improved device is simple in construction, can be inexpensively manufactured, and will be found very useful under many circumstances.

The device will be found particularly useful in erecting telegraph poles, smoke stacks 95 and in handling small wrecks especially in connection with street railways, where the overhead trolley system is employed, as the boom or mast can be quickly lowered to enable the apparatus to pass under the 100 trolley wires and then elevated and disposed in operative position when the locality where the derrick is to be operated is reached.

The preferred embodiment of the invention is disclosed in the drawings and set forth in the specification, but it will be understood that any modifications within the scope of the claims may be made in the construction without departing from the principle of the invention or sacrificing any of its advantages.

When the boom or mast 21 is to be disposed in inoperative position, by sliding it through the sleeve 20 as shown by dotted lines in Fig. 1, the hoisting appliance 30 will preferably be coupled by the hook member 32 of its lower pulley block member, to some portion of the device, as indicated by dotted lines in Fig. 1, for instance to an eye bolt near the band 22, to hold it temporarily and prevent it swinging about while the apparatus is being transported.

I claim:

1. In an apparatus of the class described, a wheel supported body including a platform having a rearwardly opening recess, a standard supported by said platform, a swivel device rotative relative to said standard, a clip device swinging relative to said

swivel device, and a boom device slidable through said clip device, whereby the boom 20 may be disposed within said recess with its lower end engaging the ground on which the body is supported.

2. In an apparatus of the class described, a wheel supported body including a platform, a standard supported by said platform and carrying a socket, a swivel device rotative in said socket and having a perforated ear, a clip device swinging upon said ear, and a boom device slidable through said clip device, whereby the boom may be disposed with its lower end engaging the ground on which the body is supported.

In testimony whereof, I affix my signature hereto.

PHEE EDWARD PETERSEN.
